(57) **CLAIM**

The ornamental design for a configurable vehicle bull-bar, as shown.

DESCRIPTION

FIG. 1 is a front top perspective view of a configurable vehicle bull-bar, showing my new design;

FIG. 2 is a front elevation view thereof;

FIG. 3 is a rear elevation view thereof;

FIG. 4 is a top plan view thereof;

FIG. 5 is a bottom view thereof;

FIG. 6 is a left side elevation view, the right-side elevation view being a mirror image thereof, and

FIG. 7 is a right-side elevation view taken through section 7-7 from FIG. 2 thereof;

FIG. 8 is a rear bottom perspective view thereof; and,

FIG. 9 is a reduced size exploded front top perspective view. The broken lines in the figures illustrate portions of the configurable vehicle bull-bar and forms no part of the claimed design.

1 Claim, 7 Drawing Sheets
